ABSTRACT OF THE DISCLOSURE

An annular loader for toy cylinder-pistols and the like is formed of an annular support portion and a plurality of similarly shaped flexible arms secured to the annular portion. The arms extend outwardly from the annular portion at an angle to its radial direction. The ends of the arms spaced from the annular portion are arranged to receive an explosive charge. Due to the flexible character of the arms their ends may be disposed in circles of varying diameters to fit different toy pistols.

SUMMARY OF THE INVENTION

In the field of the toy-arms ammunition, ammunition assemblies (loaders) are known, which allow the simultaneous charging of all the seats or chambers disposed in an annular arrangement, provided in toy-pistols of the revolving cylinder kind or equivalent toy-arms. Generally, these assemblies or loaders have a circular or annular development and are prepared for definite toy-arms; it is known in fact, that toy-arms of the above-mentioned kind are not standardized for the number of seats for dishes or containers holding explosive charges nor for the diameter of the circumference extending through the centres of the seats, nor are the numbers of seats equal. Therefore, it follows that annular loaders prepared for the same number of shots or explosive charges do not fit arms of different kinds, owing to the above-mentioned diameter variations.

The object of the present inventions is to afford a loader having the ability to vary the diameter of the circumference extending through the centres of the dishes or containers holding the explosive charges, this variation being also of considerable importance and therefore such as to allow the adaptation of the loader for toy-arms of different kinds which have equal number of seats for the explosive charge. Substantially, according to the invention, a loader comprises a continuous annular portion from which arms or appendixes extend outwardly at an angle to the radial direction, each appendix carrying (or respectively forming) at its outer or free end an explosive charge in a container, generally in a cylindrically shaped form. By this arrangement, owing to the fact that the arms or appendixes are flexible, it is possible to modify the distance of the explosive charge containers—carried by the free ends of the appendixes—from the centre of the loader. In one preferred embodiment, the appendixes extend outwardly in a substantially tangential way from the continuous portion. At the ends of the appendixes concavities, such as glass-shaped dishes, cup-shaped cavities, such as cylindrically shaped containers are advan-

2

tageously provided, in order to receive explosive material, or to form seats in order to receive independent containers holding the explosive charges.

The invention will be now better understood by means of the specification and the enclosed drawing, which shows a practical and not limitative example of the invention.

In the drawing:

FIG. 1 shows a loader for twelve shots according to the invention;

42—89

FIG. 2 shows a diametrical section substantially along the line II, II of FIG. 1;

FIG. 3 shows a loader for eight shots; and

FIG. 4 shows a section along the line IV, IV of FIG. 3.

In the drawing, a loader is indicated having a continuous annular portion 1 of a smaller diameter than the diameter of the circumference C, which extends through the centres of the seats of the explosive charges (or respectively of the containers holding the explosive charges themselves). Extending tangentially from and connected to the annular portion 1 are lightly bent appendixes or arms 3, each of which presents at the end an expansion or enlarged section 3A constituting directly the container for an explosive charge (or respectively forming the seat for a separate container) and therefore without a gap in comparison to the material of the portion 1 and 3. The appendixes 3 are flexible and, as a result, are capable to a limited degree of being deformed outwards or inwards in comparison to the rest condition, so as to modify and therefore to reduce or to increase the circumference C, also within relatively considerable limits.

Therefore the loader can adjust itself to different diameters for the circumference of the centres of the seats for the containers in the drum of the toy-arms or the like. This allows the annular loader to fit a large range of toy-arms which have an equal number of seats for the explosive charge containers, with also valuable differences of the annular arrangement of the seats for the containers.

In FIGS. 3 and 4 is provided a loader for eight shots or explosive charges, while in FIGS. 1 and 2 a loader is provided for twelve shots.

Of course the drawing shows only an example given as a practical embodiment of the invention, the latter being able to change in form and arrangements.

I claim:

1. An annular loader for toy cylinder-pistols and similar toy arms comprising a continuous annular portion, a plurality of arms secured to said annular portion and extending therefrom at an angle to the radial direction of said annular portion, said arms being flexible relative to said annular portion, means formed at the ends of said arms spaced from said annular portion for receiving an explosive charge whereby due to their flexible character said arms are movably positionable relative to said annular portion whereby the distance of said means relative to the center of said annular portion can be varied.

2. An annular loader as set forth in claim 1, wherein said arms are of a similar shape and extend outwardly from the radially outer surface of said annular portion.

3. An annular loader as set forth in claim 2, wherein said arms extend tangentially to said annular portion.

4. An annular loader as set forth in claim 1, wherein

said means comprises a cylindrically shaped container arranged to contain an explosive charge.

5. An annular loader as set forth in claim 1, wherein said means comprises a concavely shaped member arranged to receive an explosive containing member.
